KNITTING MACHINE

Robert H. Lawson, Pawtucket, and Arthur N. Cloutier, Lonsdale, R. I., assignors to Hemphill Company, Central Falls, R. I., a corporation of Massachusetts

Application August 3, 1935, Serial No. 34,580
In Canada August 30, 1934

17 Claims. (Cl. 66—43)

This invention deals with a new method and new mechanism for reciprocatory knitting and especially reciprocatory knitting as employed in the manufacture of split-foot stockings. The invention is illustrated as applied to a circular knitting machine of the Banner type wherein the leg and instep of a stocking are to be knitted at the auxiliary side of the machine, but this is not to be considered a limitation since the method and mechanism may be applied to any machine wherein the usual split-foot fabric formed by reciprocatory knitting is to be produced.

In the drawings:

Fig. 1 represents a section of fabric knitted during rotary work;

Fig. 2 shows a section of the fabric as it actually appears when knitted in a reciprocatory manner without the use of the present invention;

Fig. 3 shows a section of fabric knit in a manner similar to that of Fig. 2, except that the mechanism of this invention has been employed;

Fig. 4 is a plan view of enough of the machine to show how our mechanism has been applied thereto;

Fig. 5 is a view in elevation taken from the left hand side of the machine, the mechanism comprising the invention being illustrated in the same position shown in Fig. 4;

Fig. 6 is a sectional view of a portion of the sinker cap showing the cams therein at the auxiliary side;

Fig. 7 is a view showing in section a fragment of the sinker cap, the side sinker cam and flopper cam being shown in detail;

Fig. 8 is a plan view similar to Fig. 4 but showing the position of parts during the reverse stroke of reciprocation;

Fig. 9 is a plan view partially in section showing the auxiliary cam block assembly;

Fig. 10 is a view similar to Fig. 4 but showing the mechanism comprising the invention in an inoperative position;

Fig. 11 is a view of the mechanism as seen from the back of the machine;

Fig. 12 is a section showing the action of needles and sinkers according to the method employed in practicing the invention;

Fig. 13 is a sectional view showing a modified form of the invention wherein sinkers are raised during stitch drawing;

Fig. 14 is a sectional view similar to Fig. 13, but showing the needle in a position wherein it is drawing a stitch;

Fig. 15 is a sectional view similar to Fig. 13

but showing the sinker in lower position, the stitch being cast off at this time;

Fig. 16 is a sectional view showing the means of mounting the auxiliary cylinder;

Fig. 17 is a sectional view showing a detail of the auxiliary cylinder holding screws;

Fig. 18 is a detail view showing the adjusting screws for the same;

Fig. 19 is a sectional view showing a detail of the stitch ring;

Fig. 20 is a plan view of the auxiliary cylinder mounting ring as seen from below;

Fig. 21 is a fragmentary view of sinkers and auxiliary sinker cams as seen from above; and

Fig. 22 is a sectional view of the auxiliary cylinder showing sinker raising cams thereon.

Referring to Figs. 1 and 2, we have shown practically what happens when knitting a stocking wherein the leg portion is knitted in a circular manner and the ankle and foot portions in a reciprocatory manner to produce the usual split-foot stocking. The actual fabric made by knitting in a circular fashion appears to the eye to be formed of loops which are substantially true in form, that is, the sides of each loop are of about the same length and do not lean to either side of a line drawn vertically through any particular wale. With regard to the plain fabric, Fig. 1, it can be seen that the sides of loops are not of exactly the same length and that the tendency of these loops is to lean slightly in one direction, however, in the actual fabric this is not apparent to the naked eye.

When split-foot knitting is started either at the top of the high-splice or at the termination of the heel, as the case may be, the fabric produced will appear very much like that indicated in Fig. 2. In alternate courses, loops will be formed having unequal length sides and which also slant in opposite directions.

Taking a particular needle wale indicated by letter A, loops in alternate courses are composed of short sides 1 and long sides 2 which cause the loops to lean to one side, so that a zigzag effect is produced which is very objectionable in the stocking itself. This stocking must be subjected to further treatment in an attempt to eliminate this defect, usually without completely satisfactory results. When a portion of fabric knitted as shown in Fig. 2 is viewed from an angle it appears to be composed of alternate raised and depressed lines or streaks. This effect is more pronounced when stockings are knitted in old machines which are badly worn, and is known in the trade as "washboard" effect. Whereas,

in the plain fabric of Fig. 1, the eye was deceived into seeing what appeared to be straight wales of perfect loops since these loops all slant in one direction the opposite is true of the split fabric 5 of Fig. 2 wherein an illusion is created which multiplies the actual defect of each loop. This is apparently due to the fact that loops of adjacent courses slant in opposite directions. The applicants have discovered that if sinkers are 10 so controlled immediately after stitches have been drawn at the knitting point as to extend or push sinker loops inwardly, these same loops and their adjacent needle loops will be straightened up so that their sides will become substantially of the same length. While this method 15 of controlling sinkers may be employed in each course, that is, during reciprocations in both directions, it has been found that perfectly satisfactory results may be obtained when dealing 20 with reciprocations in one direction only, i. e., in every other course. In case the action of sinkers occurs in every other course only, a harsher action must be resorted to, and in actual practice, loops will be straightened and pushed 25 around until they may lie in a direction slightly reverse to that in which they first inclined. At the same time a sinker is trueing a loop in the course which has just been knitted, that particular loop apparently tends to work in the loop of 30 the course previously knitted and to straighten that loop also. By employing this invention during knitting of the split portions of the fabric, results such as indicated in Fig. 3 are obtained and the fabric as it is removed from the machine, will not show any apparent difference between portions knit in the circular manner and those knitted by reciprocation.

Referring to Figs. 4-11, a needle cylinder is shown at 3, a carrier ring post at 4 and a carrier ring 5 having an extension 6 pivoted to said post in the usual manner. An auxiliary cam block 7 is adapted to be moved in and out of active position in the usual manner and carries a center cam 8, Figs. 9 and 11, as well as stitch cams and a needle raise cam such as are commonly employed at the auxiliary side of a split-foot knitting machine. The cam block is supported upon cam plate 9 and slides radially being guided by angular clamps 10 and 11.

50 The usual sinker cap 12 has fixed therein a sinker side cam 13 of the usual construction and opposed to this, a similar side cam 14 which is of a thickness approximately $\frac{1}{2}$ that of the first mentioned cam. For measuring stitches, casting off, etc., these side cams function in the usual way. Center sinker cam 15 is attached to a stem 16 which is guided radially within a groove formed in the top of sinker cap 12 and plate 17 which is attached to said cap. This center cam 55 is normally in a position such as shown in Figs. 4 and 6 when knitting at the auxiliary side but is pushed radially inward against the tension of a spring 15' so that it does not act to withdraw sinkers during knitting of the heel and toe of a stocking or at any other time when knitting 60 is to be discontinued at this side of the machine.

The position of this center cam is controlled along with the yarn guide (not shown) which feeds to the needles at this side of the machine. 70 A cam 18 having a stem 19 projecting therefrom has an arcuate surface upon which a pin 20 attached to element 16 bears. Referring to Fig. 11, a post 21 has pivoted thereon at 22 a lever 23 which is controlled along with the auxiliary center cam 8, by means of a link 25, connected

at extension 26 to lever 27. A stem 19 of cam 18 has attached thereto a hooked finger 28. The hooked end 29 engages lever 23 so that when that lever is swung into position shown in Fig. 11, which position is assumed whenever the yarn guide at the auxiliary feed is withdrawn from active position, cam 18 will be pushed inwardly and the center sinker cam 15 will at the same time be projected inwardly to a position wherein it will not retract sinkers. This control of the 10 center sinker cam 15, cam 18 and also cam 8 is well known in the Banner split-foot machine and is described to this extent, merely for purposes of setting forth enough of the operation to lay a basis for the description of operating 15 the controlling mechanism for the flopper cam which is to be described later.

In Figs. 4, 5, 6, 7, 8, 10 and 11, flopper cam 30 is shown in active and also inactive positions. This flopper cam rests within a slot in sinker 20 cap 12 directly beneath side cam 14. The flopper cam pivots about a pin 31 projecting up from cap 12 and is free to be swung inwardly against sinker butts as shown in Fig. 6 or to be swung outwardly into the position of Fig. 7, the extending end 32 of said cam acting as a stop when it strikes against the beveled portion of the sinker cap. Flopper cam 30 has an extension 33 projecting from a point near its forward end and a pin 34 extends upwardly from this projection to contact with a cam to be described later. Flopper cam 30 also has its butt engaging surfaces of practically the same curvature as those on fixed cam 14. Pivot 31 is arranged in such a position that the point 35 of cam 30 is spaced a slight amount from point 36 of cam 14 so that when in active position the working surface 37 of cam 30 practically forms a continuation of the working surface 38 of cam 14, see Fig. 6.

A bracket 39 is attached as shown in Fig. 5 to 40 carrier ring post 4 and has a movable cam 40 resting thereon, said movable cam being pivoted about a pin 41 and also being slotted at 42 so that it may slide lengthwise of bracket 39. A spring 43 attached at one end to the bracket and at its other end to cam 40 normally tends to draw that cam into the position shown in Fig. 10. A lever 44 is pivoted at 45 on post 21 and has a link 46 pivoted to its opposite end at 47, said link being connected at 48 to one end of movable 50 cam 40.

Lever 44 passes behind the upper projecting end of lever 23 so that when that lever is in the position shown in Figs. 4 and 8, a position assumed when the auxiliary feed becomes active 55 such as in knitting the leg and instep of a stocking, cam 40 will be drawn against the tension of spring 43 into a position wherein it may engage the projecting pin 34 on the flopper cam. In operation the sinker cap reciprocates back and forth through a small angle so that on the clockwise reciprocation during split-foot knitting, the pin 34 strikes cam 40 and said flopper cam is projected inwardly as is very evident from inspection of Fig. 4. This is the reciprocation corresponding to the course of loops which are straightened or trued up. During the counter-clockwise reciprocation, Fig. 8, pin 34 is not in connection with cam 40 and cam 30 would merely be pushed out to the position shown in that 70 figure as sinker butts pass by it. During circular knitting as in the leg of the stocking, the condition shown in Fig. 8 prevails.

It is quite evident that the mechanism provided for straightening loops during reciprocation in

one direction might also be provided at the other side to be effective during the opposite reciprocation. If such mechanism were provided it would merely be necessary to withdraw one of the cams corresponding to 40 from operation while knitting in a circular fashion.

Bracket 39 is formed with an upwardly extending lug 49 through which an adjusting screw 50 is threaded. This adjusting screw bears against cam 40 and is used to control that cam for varying the extent to which flopper cam 30 will be projected inwardly. A lock-nut 51 may be tightened against lug 49 for maintaining this adjustment permanently. This adjustment merely has to be made at the start of knitting a particular length of stitch and yarn, and by inspection of the fabric, the machine operator can tell when he has flopper cam 30 acting upon sinkers in just the proper manner to neutralize the washboard effect, which has been illustrated in Fig. 2.

Figs. 10 and 11 show cam 40 and its operating mechanism in the positions which they assume when knitting the heel and toe of the stocking or at any time when the auxiliary feed is inactive.

In such position cam 40 is drawn by spring 43 beyond a point where it might be contacted by pin 34 as the sinker cap oscillates back and forth during reciprocatory knitting. It may thus be seen that flopper cam 30 is controlled automatically during the various phases of knitting a split foot stocking.

In Fig. 12 we have shown how sinkers are projected inwardly by the point of flopper cam 30 to straighten up stitches which have already been drawn a few needles in advance of that point. The arrow indicates direction of rotation. The sinker 52 is considered to be at the point of cam 30 and is projected inwardly extending its corresponding sinker loop and at the same time, reeling that loop about adjacent needles 53. That particular sinker loop being straightened as shown, also has a tendency to straighten up the adjacent course which was previously formed.

Referring to Figs. 13-20, we will now describe a modified form of the apparatus for accomplishing substantially the same result which was accomplished by the first form. It has been found that if stitches are drawn by the conjoint action of needles and sinkers during reciprocatory knitting, the resulting fabric will fairly closely approximate that which was formed during circular knitting, see Fig. 1, no matter whether that fabric was produced of stitches drawn by needles alone or by sinkers and needles. It has further been discovered that if sinkers are used to assist in stitch drawing in one direction of reciprocation and in the other direction stitches are drawn by needles alone very satisfactory results will be obtained. In this case the stitch cams must be adjusted so that the stitch drawn by a needle over a stationary sinker will be substantially of the same length as a stitch drawn by the same needles but by a different stitch cam, part of the stitch being drawn by a moving sinker.

Referring to Fig. 13, a needle cylinder 54, herein shown as of the rotary type but not necessarily so limited, is permanently attached to a ring gear 55 which rotates within a circular base 56. A sinker head 57 is clamped to said cylinder and has sinkers 58 of the type better shown in Fig. 14, which are adapted to be rocked about their outer ends when actuated by certain sinker cams to be described hereinafter. A sinker cap 59 of the usual type having sinker cams therein

completes this assembly and serves to operate said sinkers during rotary or reciprocatory knitting. Needles 60 preferably of the latch type reciprocate in tricks cut in said cylinder. A stitch ring 61 of special design is fixed to the upper end of said cylinder and this stitch ring will be described in greater detail later.

Within this rotary needle cylinder a relatively fixed auxiliary sleeve or cylinder 62 is mounted so that it may be adjusted in a vertical direction. This sleeve is better shown in Figs. 16, 21, 22 and the mounting therefor in Fig. 20.

Referring to Figs. 16 and 20 a ring 63 having projections 64 and 65 is attached to the under side of the circular base 56 by means of said extension. Extension 64 is permanently bolted to a machined surface at one side of this element 56 and extension 65 projects through a slot in widening pick bracket 66 which bracket is in turn fixed to the circular base. Three screws 67 pass through ring 63 and are threaded within a flange at the lower end of said auxiliary cylinder. These screws serve to maintain said cylinder downwardly in a boss wherein its flanged lower end bears against adjusting studs 68. These studs are herein shown as three in number and are threaded within said ring being locked in their adjusted position by means of lock-nuts 69.

Cylinder 62 carries at its upper end equally spaced on either side of the auxiliary yarn feed point (not shown) two cams 70, 71, which serve to raise the inner ends of sinkers during knitting at said feed point. Each cam is provided with a flanged extension 72 which has slots 73 through which pass screws for clamping the same to the auxiliary cylinder. These cams may be adjusted to their proper positions by loosening these mounting screws and sliding the cams about the upper surface of said cylinder.

By the adjustment for said sleeve, previously described, it is possible to regulate the upward movement of sinkers and thus to vary stitch length by sinkers as well as by the usual stitch cam. The sinker will be positively elevated by its cam 70 or 71 as the case may be, but excessive movement is limited by a spring 74 which is retained within an annular groove in the special stitch ring 61 shown in detail in Fig. 19. In operation a sinker will be raised by one of the cams in drawing a stitch and that same sinker will cast off its loop prior to being again raised by the second cam, at which time a needle will have been raised to the position shown in Fig. 13 so that this second upward motion of the sinker has no effect on stitches previously drawn as they are merely held idly about the shank of a needle. As before stated, it has been found that more satisfactory results have been obtained when only one of the cams 70, 71 is used. In such case alternate courses of reciprocating knitting will be formed by needles alone, while the intervening courses will be formed of loops drawn by conjoint action of needles and sinkers. The effect of such a method of knitting is to greatly improve the quality of fabric knitted thereby, and in cases, such split fabrics very closely approximate that which has been knitted by circular knitting.

The invention has been described relative to split foot knitting at the auxiliary side of a machine which knits both leg and instep of the same yarn but is not in any way limited to such a use, since it may be employed in any knitting machine wherein reciprocatory knitting takes place and results in distorted loops such as have been shown in Fig. 2. Many changes may occur to one skilled

in the art and we are not to be limited except by the scope of the appended claims.

We claim:

1. An independent needle knitting machine having knitting instrumentalities including needles and sinkers, and cams for controlling the movements of the said knitting instrumentalities, the knitting instrumentalities and cams being relatively reciprocable, one of the said cams being operable during such reciprocatory knitting to advance the sinkers abnormally immediately following the drawing of the stitches to effect the knitting of uniform stitches in adjacent courses.
2. In a circular knitting machine having needles and sinkers independently mounted therein, cams for acting upon the needles and sinkers to effect the knitting of fabric, the needles and sinkers being reciprocable with respect to the cams, one of the said cams acting upon the sinkers to advance them, a supplemental cam acting upon the sinkers during reciprocatory knitting to impart an abnormal advancing movement to the sinkers immediately following the drawing of stitches to effect the knitting of uniform stitches in adjacent courses, said cam being movable to an active position to advance the sinkers as aforesaid and being movable from the said position to a relatively inactive position where the movements of the sinkers are not affected, and means for moving the said cam last mentioned to its active position.
3. A circular knitting machine having independent needles and sinkers, cams for acting upon the said needles and sinkers to move them to effect the knitting of fabric, there being relative reciprocatory movements between the cam means on the one hand and the needles and sinkers on the other hand, two of the cams acting upon the sinkers during successive reciprocations, a supplemental and movable cam acting in conjunction with one of the two aforesaid cams for imparting an abnormal advancing movement to the sinkers during a relative reciprocation of the cam means and the needles and sinkers in one direction, the construction and operation being such that the abnormal advance of the sinkers effects the knitting of uniform fabric.
4. A knitting machine having in combination a sinker cap for a knitting machine and a movable cam therein for acting upon sinkers during reciprocatory knitting, means for advancing the said cam at predetermined times, said means including a movable cam which in one position is effective to advance the cam first mentioned and in another position is ineffective for that purpose, means effective during reciprocatory knitting for moving said second mentioned cam to and from its effective cam engaging position.
5. An independent needle knitting machine having knitting instrumentalities and cams for acting upon them, there being relatively circular and reciprocatory movements between the cams on the one hand and the knitting instrumentalities on the other, the instrumentalities including sinkers, and means for acting upon the sinkers to advance them abnormally and immediately after drawing stitches, during reciprocatory movements in one direction to effect the knitting of uniform fabric, the said sinker advancing means being ineffective during circular movements.
6. A sinker head for use in a knitting machine and having a movable cam mounted therein, means for acting upon the cam to advance the same, said means at other times being ineffective

for the purpose stated, auxiliary means for moving the said means to one of said positions and spring means for moving the said means to the other of said positions.

7. A sinker head for use in a knitting machine and having a movable cam mounted therein and a second cam effective thereupon to move the movable cam to an active position, said second mentioned cam being movable to a position where it is ineffective during heel and toe knitting to advance the cam first mentioned.

8. A sinker head for use in a knitting machine and having a movable cam mounted therein and a second cam effective thereupon to move the movable cam to an active position, said second mentioned cam, being movable to a position where it is ineffective to advance the cam first mentioned, the means for moving the second cam as aforesaid consisting of levers 23, 44 and connections leading to the said second mentioned cam.

9. An independent needle knitting machine having a needle bed and knitting instrumentalities including needles and sinkers mounted therein, a member mounted in the needle bed for acting upon the sinkers to move them in combination with the needles to advance them abnormally during reciprocatory movements in one direction to effect the knitting of uniform fabric, said member being adjustable to vary the movements imparted to the sinkers.

10. A sinker head for a knitting machine, sinkers mounted therein and cam means for raising the sinkers by advancing them abnormally during reciprocatory movements in one direction to effect the knitting of uniform fabric, and means adapted to engage the sinkers to limit their upward movement.

11. A sinker cap for a knitting machine having a cam therein for at times advancing sinkers abnormally, a second cam for acting upon the first cam to advance the same, means for effecting movement of the second cam to a position where it does not advance the sinker engaging cam during heel and toe knitting.

12. An independent needle knitting machine adapted to knit a stocking having circular courses and split-foot courses and having an auxiliary feeding station for effecting the knitting of the continuous circular portions of the stocking and of the instep of the split-foot portion of the stocking, a sinker cam for abnormally advancing sinkers during reciprocatory courses and immediately after drawing stitches in which the knitting is effected by relative reciprocatory movements of the instrumentalities and cams in a direction opposite to the direction of relative movement of said instrumentalities and cams in effecting the knitting of continuous circular courses.

13. An independent needle knitting machine adapted to knit courses by relative reciprocatory movements of the instrumentalities and cams, a cam for abnormally advancing the sinkers immediately after drawing stitches and during relative movements in one direction of the cams on the one hand and the knitting instrumentalities on the other hand but not effective to advance the sinkers in the opposite direction of reciprocation.

14. An independent needle knitting machine adapted to knit courses by relative reciprocatory movements of the instrumentalities and cams, a cam for abnormally advancing the sinkers during relative movements in one direction of the cams on the one hand and the knitting instru-

5 mentalities on the other hand but not effective to advance the sinkers in the opposite direction of reciprocation, the ineffectiveness of the said cam being the result of the shifting of the sinker cap incident to reversals in the directions of rotations of the needles.

15. A circular, independent needle knitting machine having needles and cooperating sinkers therein, cams for controlling the needles and 10 sinkers in rotary and reciprocatory knitting, and means functioning on sinkers in one direction of reciprocation, at least, to impart to said sinkers an additional movement inwardly, immediately after drawing stitches, for causing loops which 15 have been drawn to incline in one direction, to be straightened and aligned with the direction of their individual wales.

16. An independent needle knitting machine having knitting instrumentalities including needles and sinkers, and cams for controlling the 20 movements of the said knitting instrumentalities,

ties, the knitting instrumentalities and cams being relatively reciprocable, one of the said cams being operable during such reciprocatory knitting abnormally to advance the sinkers radially immediately following the drawing of the stitches 5 to effect the knitting of uniform stitches in adjacent courses.

17. An independent needle knitting machine having knitting instrumentalities including needles and sinkers, cams for controlling the movements of said knitting instrumentalities during reciprocatory knitting to effect simultaneous knitting of two joined fabric sections, said cams including a cam operable during such reciprocatory knitting abnormally to advance sinkers immediately following the drawing of the stitches 10 to effect the knitting of uniform stitches in adjacent, reciprocatorily knitted courses. 15
